UNITED STATES PATENT OFFICE.

OTTO P. TORNGREN, OF EVERETT, MASSACHUSETTS.

AUTOMATIC VALVE.

Application filed July 17, 1922. Serial No. 575,645.

To all whom it may concern:

Be it known that I, OTTO P. TORNGREN, a citizen of the United States, residing at Everett, in the county of Middlesex and State of Massachusetts, have invented certain new and useful Improvements in Automatic Valves, of which the following is a specification.

This invention relates to improvements in automatic valves. More especially it relates to valve apparatus for a domestic or other hot water supply system having a storage tank, sometimes known as a "kitchen boiler." Much trouble arises when such are operated in direct connection with a city water supply system, because of the high pressure. The theoretical advantages of direct connection are many and are well known, but objections are found in the risks of collapse, or explosion, and in the necessity for very strong materials, with high cost, and with danger of leakage. So far as I am aware no satisfactory arrangement is known for direct connection with a city system having the service pressures that are commonly found. It is an object of the invention to avoid these objections in apparatus which can be direct-connected to city pressure service; and so also to avoid the expense, foulness, constant care, and occasional dangers, of the old familiar attic tank with float valve. The present invention accomplishes the paradoxical result of affording direct connection with the high pressure supply pipe and yet preventing the boiler from experiencing its pressure. This is done by switching the boiler automatically to atmospheric pressure when no call is being made upon it for water; and switching it automatically to the said supply when a faucet is opened anywhere in the system to draw water from the boiler. Not only is it open to the supply only during the limited times while flow continues; but moreover the pressure during such flow is considerably less than under static conditions.

For protecting a boiler against expansion due to heat the only devices, now in use, I believe, are in the nature of safety valves or safety fuses which automatically open or give way when the predetermined safety limit of pressure or temperature is passed. Such devices, however, are subject to corrosion, and for some other reasons have not proven entirely satisfactory, and sometimes

fail to function. Furthermore, since no such devices affect the flow through the boiler in any way, there is no indication, if one is out of order, until the tank has given way. It is therefore useful that a positive relief be provided for the boiler pressure, and that it be one whose action is directly associated with the flow through the boiler so that if it gets out of order, that fact will be a warning at once.

It is therefore, a main object of the present invention to provide a safety device which will always permit normal flow of water from the pressure service into the boiler when water is drawn; circulation from boiler to fire and back to boiler at all times; discharge from the boiler through the distributing pipes in the regular way; and yet will keep the boiler under merely atmospheric pressure when distribution is not occurring. A further object is the provision of a constant pressure supply to the distributing pipes of the system beyond the boiler even when the boiler itself is shut off from the supply pressure. These objects are accomplished by providing two connections between the supply line and the distributing line, one of which leads to the boiler and thence to the distributing pipes, and the other of which leads direct from the supply line to the distributing line, by-passing the boiler. Each of these branches of the supply is controlled by a separate valve, and these two valves are associated in such manner that as one opens the other closes. Accordingly, when the branch through the boiler is open, and flow through a faucet is occurring, the by-pass will be shut off; and when the faucet is closed and flow ceases, the valves move to shut off the boiler from the supply and to connect the supply to the faucets. This last movement of the supply valves is accomplished by the supply pressure itself acting on a third or vent valve, provided in a vent passage which opens the distributing line to atmosphere at a point between the boiler or tank and the place where the by-pass leads into the distributing line. This vent valve is closed during flow, so that no water or pressure escapes; but, upon all outlets being closed and the flow stopped, the pressure which at once builds up in the tank and the distributing system, then acts to force this vent valve from its seat, and by means of a system of linkage, connecting its stem with the supply

valves forces them to alter their positions so as to cut off the supply valve of the tank and to open the by-pass valve. The pressure then supplied through the by-pass at 5 once acts to maintain the supply valves in their altered positions, for the effective area of the by-pass valve plunger upon which this pressure is exerted, is greater than the area of the valve plunger closing the direct 10 supply passage; and since these valve plungers are directly connected with each other, this unbalanced force will continue to keep the valves in the positions described, as long as the pressure on the by-pass valve continues above a predetermined point. As the supply pressure is thus cut off from the boiler through the direct branch to it, the 15 vent valve is fully opened and the tank vented to atmosphere. A check valve, interposed between the by-pass connection to the discharge line and the vent passage, is closed by the pressure in the discharge line supplied through the by-pass, and thus cuts off this vent so as to prevent escape of water in the 20 discharge line through this vent. This condition prevails until some faucet is opened. Thereupon, immediately water flows out from the discharge pipe at a faster rate than it can be supplied through the restricted by-pass; which flow produces instant lowering of the pressure in the discharge pipe. As the pressure acting on the by-pass valve falls below the point necessary to keep it open, the full supply pressure, 25 which is constantly acting on the valve controlling the direct branch to the boiler, causes the two supply valves to shift thereby cutting off the by-pass passage and opening the supply direct to the tank. And this 30 shifting of these valves closes the vent valve by virtue of the linkage between them already mentioned. The check valve will open for flow through the tank, and discharge will continue until all faucets are 35 again closed.

The apparatus may be embodied in a relatively simple compact structure, in which the supply and the by-pass valves have a common stem, with one of these valves at 40 each end, and the vent valve is near by, with a mechanical leverage connection to said stem, by which it is interlocked, so that all three valves move simultaneously in either direction. The motive power is the pressure of the water supply. This is manifest indirectly, as momentum, in the water flowing from the boiler when a faucet is closed, sufficient to overcome the pressure at supply entrance; and is manifest directly, as a static 45 opening pressure on the supply valve, whenever the resisting pressure is relieved by the opening of a faucet. On another simple embodiment of the invention these two valves are on separate stems, connected by leverage. The accompanying drawings

show these two of the several possible forms of apparatus which may be made in accordance with the principles of the invention. It is intended that the patent shall cover by suitable expression in the appended claims, 70 whatever features of patentable novelty exist in the invention disclosed.

In the accompanying drawings,

Figure 1 is an elevation in section of apparatus embodying the invention showing the parts in their relative positions when the system is static;

Figure 2 is a similar elevation on line 2-2 of Figure 3, of a modified form, with the parts arranged as when flow occurs; and

Figure 3 is an end view from the left of Figure 2.

Referring to the drawings, the pipe 10 represents a supply line, such as a pipe connected with and served by city water system, and 12 indicates the hot water distributing system of a building, herein called "the discharge," having the usual outlets or faucets 14 for discharge. The apparatus embodying the present invention is preferably located at that end of the hot water tank or boiler 16 to which the supply pipe is ordinarily connected and from which the discharge pipe leads. It is installed in such manner that its upper end constitutes as it were a portion of the boiler supply line (10, 10') and its lower end forms a part of the boiler discharge line (12', 12). In the embodiment shown in Fig. 1, the apparatus comprises several sections joined together, including a horizontal base portion 18 from which rise two vertical legs, 20, 22 near together, one low and the other relatively high. The supply pipe 10 enters the top portion of the long leg, 22, so that the service supply water at full pressure is constantly in the upper end of a chamber 24 therein. This chamber is divided into upper and lower compartments 24', 24'' by a partition 26, having an opening 28 therethrough whose effective size may be altered by an adjustable reducing-valve 30 to regulate the amount of flow to the tank. From the lower compartment 24'' the supply passage continues through a short connecting pipe 10' to the boiler. This supply passage, hereinafter referred to as the main supply passage or branch, is controlled by a plunger valve 32 movable in the lower compartment 24'' and seating upward, against the supply pressure, toward a seat formed around the said opening 28. As shown in Fig. 1 this valve is closed, so that no water can pass through the opening 28 to the tank.

The plunger body or stem of the valve 32 extends downward through the vertical leg 22, through suitable packing glands 34 and 36, arranged above and below an open frame work section 38 of the leg, into a chamber 40 in the portion of the leg next adjacent

to the horizontal base section 18. This lower chamber has upper and lower compartments 40' and 40" made by a partition 42 whose upper side constitutes a valve seat for the lower end of the valve plunger 32. This portion of the plunger has a perforated flange 32' which slides along the walls of the upper compartment 40' and serves as a guide for the plunger. The partition 42 has an axial opening 44 which, like the opening 28 in the upper chamber, is opened or closed by the plunger 32. When the plunger is up closing the opening 28 the lower opening 22 will be open; and when the plunger is down, opening the supply passage at 28, the lower opening 44 is closed. The area of the upper opening 28 at the valve seat is somewhat less than the area of the opening 44 at its valve seat. This is so that equal intensity of pressure on the top and on the bottom of the plunger, will result in the plunger staying up, as illustrated. Such equality of intensity of pressure on both ends of the plunger is effected by providing a small passage 46 from the compartment 24' to the compartment 40' conveniently made in the walls of the sections of leg 22. Its effective size can be altered by a restriction valve 46' controlling its opening into the chamber 40. This passage is the auxiliary supply branch or by-pass connecting the supply 10 with the discharge 12 for the lower chamber 40 in the leg 22 is in open communication with the discharge end of the horizontal leg 18, of which the discharge pipe 12 is a continuation. When the plunger valve 32 is up, the service high pressure is transmitted through the by-pass to the discharge line 12. To prevent this causing back flow into the boiler through the horizontal leg 18, there is arranged in this leg a check valve 48. This valve closes an opening 43 in partition 45, located between the opening into the vertical leg 22 and the connection with pipe 12' from the tank. It is therefore evident, that with the plunger in the position shown in Fig. 1 there can be no transmission of the supply pressure to the tank, for the direct branch through the upper chamber 24 and pipe 10' is closed by the upper end of plunger 32, and the pressure in the auxiliary branch through by-pass 46 and discharge leg 18 is cut off by the check valve 48.

The tank, furthermore at this time has only atmospheric pressure. In the short vertical leg 20, rising from the base 18, is a relief or vent opening 50 leading from the discharge passage 18' through a chamber 20' and small drain pipe 60 to atmosphere. This opening is controlled by a valve 52 whose guiding stem 52' extends upward parallel with the plunger 32 and is connected therewith by an arm 54, linkage 56 and a

lever 58. The lever, being forked around plunger 32, or passing through a slot in it, and fulcrumed beyond it on the frame work of the open section 38 of the leg 22, has a pin and slot connection to the plunger 32 at 70 a suitable ratio. Because of this mechanical connection the vent valve 52 and the two valves on plunger 32 move simultaneously. When they move up, as in Fig. 1 the cutaway under part of the guide stem 52' enters 75 the opening 50, thus allowing water to escape past it from the tank 16 and base 18, relieving the tank of the service pressure. The amount of this flow is trifling, because simultaneously the supply is shut off at 28, 80 and the distribution system at 43; and atmospheric pressure prevents the column of water in 10' above the opening 50 and drain 60, from sinking. This is the position of the several parts whenever all faucets and 85 other outlets in the discharge pipes are closed.

Upon the opening of any faucet in a normal manner, the flow of water from the discharge pipe 12 reduces the pressure in the 90 compartments 40', 40", faster than it can be replaced by the restricted flow through the by-pass. Accordingly the pressure upward on the lower end of the plunger 32 instantly becomes less than that exerted downward on its upper end through the opening 28, and the plunger moves downward, opening the direct passage 10, 28, 10' through the upper compartments 24', 24" to the tank. But the plunger 32, in moving downward, 95 acts through the lever 58 to move the valve 52, down, and so to close the opening 50 from the tank to atmosphere. In consequence the service pressure at 10 is applied through the tank and discharge 18' to deliver hot water 100 of the tank at full service pressure, through check valve 48, and discharge line 12 to whatever faucet is open. If it is desired to reduce this pressure that can be done by setting down the plug 30. Flow of cold water 105 through the by-pass 46 to the discharge line is cut off by the descent and seating of the plunger 32 to close the opening 44. When the faucet is closed, the momentum of the flowing water is applied to both the vent 110 valve 52 and the main plunger 32. Both move upward, shutting off the supply to the tank at 28, and venting the tank to atmosphere at 50. The opening 44 simultaneously becomes clear for passage of water 115 under service pressure through the by-pass and compartments 40', 40" to seat the check valve 48 and to maintain the plunger 32 and the valve 52 in the positions last described. The system continues in this static condition 120 until the opening of an outlet. When the tank is thus cut off from the supply pressure and vented to atmosphere, it is under no stress from the service pressure; and when the faucet is open which is always a 125

130

relatively small part of the whole time, the very fact that the faucet affords relief prevents the pressure in the tank rising even momentarily to any considerable intensity.

5 A feature that may be incorporated in the by-pass control, if desired, is to make the guide flange 32' fit closely enough, and be long enough in the axial direction, as illustrated, so that it closes the outlet of the by-
10 passage 46 temporarily as it moves past it. Water moves through the perforations of the guide flange, as the latter rises and falls; and the momentary closure of the passage gains whatever benefit may result from cutting off the service pressure in the chamber during shifting of the valve.

In Figs. 2 and 3 a modification of the apparatus of the invention is shown, comprising a casing of only two parts 70, 72, arranged with the main supply valve 132 and the by-pass valve 132' on different axes but connected mechanically with each other and with the vent valve 152 by a walking-beam 74. The supply chamber 124 is similar to that already described except that the flow through it is upward, the supply entering its lower compartment 124' at 10 and leaving from its upper one 124'' through pipe 10' to the boiler. The tank inlet valve plunger 132 moves downward to close the opening 128 in the partition 126; and the by-pass valve 132' and vent valve 152, attached to the walking beam on the other side of the fulcrum 76 move upward simultaneously with it. The water from the boiler connection 12' enters a passage 118 in the lower part of the casing 72, and with the parts as shown, finds the branch passage 150 closed by vent valve 152, and flows through an opening 145 into the lower compartment 140' of the by-pass valve chamber 140. This opening has a cone shaped top edge to provide a seat for the check valve 146; here shown as of the ball type. The by-pass valve 132', like that already described in connection with Fig. 1 is a flanged plunger moveable toward and from the partition 142 which divides the chamber into compartments 140', and 140''. The former 140' is the delivery place of the restricted by-passage 146 leading through the wall of the casing 70 from the compartment 124' of the supply valve chamber.

The vent valve 152 is shown with its stem 152' hollow and comprising a deep cut receiving the lower end of the rod 82 which hangs at the end of the walking beam lever 74. When the vent valve is forced upward by the pressure on its bottom, its cup stem pushes the rod and walking beam ahead of it; but when the latter is in position where the supply valve is closed and the by-pass valve open, at which time there is no pressure on the tank, the vent valve 152 may return independently to its seat, under the

force of a light coiled spring 84 wound around its cup stem between its head and a plug in the top of the vent chamber 120'. This reseating of the vent valve diminishes the parts necessary to be moved when an outlet is opened for discharge, which makes the action at such time somewhat quicker. It also prevents any bubbling over of water due to ebullition while water is standing in the tank and being heated. By restraining the escape of steam to a degree, the further heating of the water is aided; but this accumulation of steam pressure is so slight, since the only force resisting its escape is the weight of the seated vent valve 152 and the small force of the coiled spring 84, that its effect upon the tank is entirely negligible. Should it reach an applicable amount it will raise the vent valve and pass out through the vent pipe 86.

85 The action of this modified type of apparatus is like that heretofore explained. The result of both forms is an automatic switching of the service water pressure, keeping it on the distribution line alone whenever all faucets are closed, and sending it through the tank whenever a faucet is opened, thus maintaining the tank under minimum stress but with all of the advantages that attend a connection of the supply pressure through the tank into the discharge line.

86 Although the invention is here described as it may be applied to a hot water storage tank, it can be applied to other uses; and the apparatus embodying it can be suitably varied according to need. The automatic switch is obviously independent of whatever type of apparatus occupies the place here shown occupied by the tank, and may be used with any character of liquid. Such apparatus may be mere piping, and is referred to in the claims by the general term of container.

Considering the invention in its broader aspects, it is to be observed that the principle underlying the by-pass which has been described is the provision of a source of power on the delivery side which shall be available for maintaining closed the supply valve at 28 and the check valve at 48 of Figure 1. 110 This power may be obtained in other ways, as for example, by storage of the energy of that water which is flowing at the time the faucet is closed, as by provision of an air chamber or other resilient chamber into which water flows on the shutting off of the outlet, and which is relieved upon the opening of the faucet so that the service supply valve would again open. Moreover the vent 50 is not necessarily opened automatically, and need not discharge water actually into atmosphere as illustrated; the principle of this being to provide relief, which may be done against a diaphragm or other resilient means in place of actually 120 125 130 135 140 145 150 155 160 165 170 175 180 185 190 195 200 205 210 215 220 225 230 235 240 245 250 255 260 265 270 275 280 wasting the liquid. However, the form which is herein illustrated has advantages such that it is deemed best fitted to illustrate the invention in general.

5 I claim:

1. A liquid storage and supply system comprising a container, a pressure supply line leading thereto and a distributing line extending therefrom, having a controlled outlet; combined with apparatus providing a relatively small by-passage past the container from the supply to the distributing line, and having means operative upon the closing of the outlet for cutting off said container from both said lines and opening the by-passage between them.

10 2. A liquid storage and supply system comprising a container, a pressure supply line leading thereto and a distributing line extending therefrom having a controlled outlet, and means for cutting off said container from both said lines; combined with apparatus providing a source of power beyond the cut off in the distributing line, operative upon the closing of the outlet and adapted to maintain closure of the cut off in the supply line.

15 3. A liquid storage and supply system comprising a container, a pressure supply line leading thereto and a distributing line extending therefrom having a controlled outlet, and means for cutting off said container from both said lines; combined with apparatus providing a source of power beyond the cut off in the distributing line, operative upon the closing of the outlet and adapted to maintain closure of the cut off in the supply line; there being a means of relief for the container, between said cut offs, operative when the supply cut off is closed.

20 4. A liquid storage and supply system comprising a container, a pressure supply line leading thereto and a distributing line extending therefrom having a controlled outlet, and means for cutting off said container from both said lines; combined with apparatus providing a source of power beyond the cut off in the distributing line, operative upon the closing of the outlet and adapted to maintain closure of the cut off in the supply line; there being a means of relief for the container, between said cut offs, inter-connected with the supply cut off and arranged for opening and closing with the closing and opening, respectively, of the supply cut off.

25 5. A liquid storage and supply system comprising a container, a pressure supply line leading thereto and a distributing line extending therefrom having a controlled outlet, and means for cutting off said container from both said lines; combined with apparatus providing a source of power beyond the cut off in the distributing line, op-

erative upon the closing of the outlet and adapted to maintain closure of the cut off in the supply line; there being a vent valve for the container, between said cut offs, and means whereby it is operative when the supply cut off is closed.

30 6. A liquid storage and supply system comprising a container, a pressure supply line leading thereto and a distributing line extending therefrom having a controlled outlet, and means for cutting off said container from both said lines; combined with apparatus providing a source of power beyond the cut off in the distributing line, operative upon the closing of the outlet and adapted to maintain closure of the cut off in the supply line; there being means of relief for the container and means holding said relief means inoperative when the cut offs are not in use, and releasing it to be operative when the supply cut off is closed.

35 7. A liquid storage and supply system comprising a container, a pressure supply line leading thereto and a distributing line extending therefrom, having a controlled outlet; combined with apparatus providing a relatively small by-passage past the container from the supply to the distributing line, and mechanism, including interconnected valves, adapted to be operated by momentum of the flowing liquid, upon closure of the outlet, for shifting said valves to close the supply and open the by-pass.

40 8. A liquid storage and supply system comprising a container, a pressure supply line leading thereto and a distributing line extending therefrom, having a controlled outlet, with means for cutting off said container from both said lines; combined with apparatus for providing a source of power beyond the cut off in the distributing line; and mechanism, including interconnected valves, adapted to be shifted, upon closure of the outlet, to close the supply and establish the source of power for holding it closed, and upon opening of the outlet, to open the supply and disestablish the source of power.

45 9. A liquid storage and supply system comprising a container, a pressure supply line leading thereto and a distributing line extending therefrom, having a controlled outlet, with means for cutting off said container from both said lines; combined with apparatus for providing a source of power beyond the cut off in the distributing line; and mechanism, including interconnected valves, adapted to be shifted, upon closure

50 of the outlet, to close the supply, establish the source of power, for holding it closed and open a relief for the container, and, upon opening of the outlet, to open the supply, disestablish the source of power, and close the said relief.

55 10. A liquid storage and supply system

- comprising a container, a pressure supply line leading thereto and a distributing line extending therefrom, having a controlled outlet, with means for cutting off said container from both said lines; combined with apparatus for providing a source of power beyond the cut off in the distributing line; and mechanism, including interconnected valves for the supply line, source of power, and for relief for the container, adapted to be operated by the momentum of the liquid upon closure of the outlet, whereby the said momentum acting upon the relief valve and the source of power valve opens them and thereby simultaneously closes the supply line valve.
11. A liquid storage and supply system comprising a container, a pressure supply line leading thereto and a distributing line extending therefrom, having a controlled outlet; combined with apparatus providing a relatively small by-passage past the container from the supply to the distributing line; and mechanism, including a valve in the supply line, a valve in the by-pass, connection whereby they move oppositely simultaneously to open one and close the other, and means to move them thus upon the closing of the controlled outlet; and a valve cutting off the container from return of the liquid that is in the distribution line.
12. A liquid storage and supply system comprising a container, a pressure supply line leading thereto, and a distributing line extending therefrom having a controlled outlet; combined with apparatus providing a relatively small by-passage past the container from the supply to the distributing line, and mechanism, including a valve cutting off the container from the supply line, a valve cutting off the container from return of liquid that is in the distribution line, a valve in the by-pass, and a vent valve for the container between said supply and distribution valves; said supply, vent and by-pass valves being inter-connected and adapted to be operated by pressure of the liquid upon them, with the by-pass and vent valves opposing the supply valve and adapted to be operated by momentum of the flowing liquid, to close the supply valve whenever the outlet for the flowing liquid is closed; the said by-passage and by-pass valve being adapted by relative area to hold the supply valve closed while the by-pass is open and outlet closed, and to permit opening of the supply valve owing to relief resulting upon opening of the outlet to normal extent.
13. A liquid storage and supply system comprising a container, a pressure supply line leading thereto, and a distributing line extending therefrom having a controlled outlet; combined with apparatus providing a relatively small by-passage past the container from the supply to the distributing line, and mechanism, including a valve in the by-pass, and a vent valve for the container between said supply and distribution valves; said supply, vent and by-pass valves being inter-connected and adapted to be operated by pressure of the liquid upon them, with the by-pass and vent valves opposing the supply valve and adapted to be operated by momentum of the flowing liquid, to close the supply valve whenever the outlet for the flowing liquid is closed.
14. A liquid storage and supply system comprising a container, a pressure supply line leading thereto, and a distributing line extending therefrom having a control outlet; combined with apparatus providing a relatively small by-passage past the container from the supply to the distributing line, and mechanism, including suitable connected valves arranged and adapted to be shifted automatically by liquid pressures in the system, to make the line of flow alternatively through the container and through the by-pass; there being a valve preventing flow from the by-pass into the container in the latter case.

Signed at Boston, Massachusetts, this 29th day of June, 1922.

OTTO P. TORNGREN.
